UNITED STATES PATENT OFFICE

JOHN R. ROSE AND EDWARD L. CALEY, JR., OF PHILADELPHIA, ASSIGNEES
TO ENOS S. SILANTZ AND OLIVER B. KEELEY, OF SPRING CITY, PA.

DESIGN FOR FRONT PLATE OF A RANGE.

Specification forming part of Design No. 7,415, dated May 5, 1874; application filed April 22, 1874.
[Term of Patent 7 years.]

To all whom it may concern:

Be it known that we, JOHN R. ROSE and EDWARD L. CALEY, Jr., of the city of Philadelphia, in the State of Pennsylvania, pattern-makers, have invented a Design for the Front Plates of a Range, of which the following is a specification:

The nature of our design is fully represented in the accompanying engraving, to which reference is made.

A represents the front plate of the range; B B, the oven-doors; C, the fire-door; D, the ash-pit door, and E the damper-plate. The front plate A has a plain flat face, with the exception of a' and a'' , the first, a' , being a slightly-raised flat panel with crossing-line ornaments, as shown, and the second, a'' , a slightly-raised flat panel thereon, as shown, both of said panels a' and a'' being directly

below the oven-door B. The oven-door plates are each made with a flat face raised outward by beveled edges b' b'' , and ornamented, as shown, on the face. The fire-door plate C has a flat face raised outward by bevel edges c' c'' , and ornamented as shown. The ash-pit door-plate D has a flat face raised outward by beveled edges d' d'' , and ornamented, as shown, near its upper edge, and with draft-openings 4 4. The damper plate E is plain and flat, as shown.

What we claim as our invention is—

The design for the front plates of a range, substantially as described and shown.

JOHN R. ROSE.

EDWARD L. CALEY, JR.
